UNITED STATES PATENT OFFICE.

JOHN W. DICKENS, OF FORT WAYNE, INDIANA.

FISH-BAIT.

1,299,432.

Specification of Letters Patent. Patented Apr. 8, 1919.

Application filed July 18, 1917. Serial No. 181,298.

To all whom it may concern:

Be it known that I, JOHN W. DICKENS, a citizen of the United States of America, and resident of Fort Wayne, in the county of

5 Allen and State of Indiana, have invented certain new and useful Improvements in Fish-Baits, of which the following is a specification.

This invention relates to improvements in 10 artificial baits for fish, and the objects thereof are to afford a bait of its class that may be adjusted selectively so as to ride upon the surface of the water as it is drawn by its line or descend to an indefinite depth beneath the 15 surface. The features of the invention consist of the peculiar formation of the head-end of the bait-body, and the manner by which one of the hook-clusters is detachably connected to the bait-body.

20 The objects of the invention are accomplished by the construction illustrated in the accompanying drawings, in which:—

Figure 1 is a side elevation of the bait with the hook attached to the body for under- 25 water use;

Fig. 2 is a similar view in longitudinal central section, and with the hook attached for surface use;

Fig. 3 is a top plan view of Fig. 1;

30 Fig. 4 is a side elevation of the device showing the manner of attaching the hook to the body;

Fig. 5 is a detail view showing a modified form of the link for connecting the hook to the body; and

Fig. 6 is a front end view of the bait-body. Similar characters of reference indicate corresponding parts throughout the several views and referring now to the same:—

40 The body 1 of the bait is composed of wood and shaped with a rear tapering portion. The head-end of the body presents a flat face 2 that lies in a plane at right angles to the axis of the body, and also a 45 slanting convex face 3 that recedes from the flat face with which it is contiguous. The flat face 2 encompasses the axial center of the body and extends to the perimeter thereof and a screw-eye 4 for the attachment of 50 the fish-line is driven into the body at the head end thereof in line with its axis.

Extending through the body at a point back of the receding face is a tube 5, in the middle portion of which are made protuberances 6 positioned in opposite pairs. The tube is adapted to admit of the insertion

therethrough of the eye 7 of the hook-cluster 8 so that the anchor 9 may be introduced into the eye.

The anchor consists of a wire bent into the 60 form of the letter U with one end 10 extending beyond the other and turned over so as to prevent its being drawn through the tube when the cluster is pulled into operating position. The opposite sides of the anchor rest 65 between the corresponding pairs of protuberances so that the anchor is thereby prevented from turning in the tube.

In Fig. 5 is shown a modification of the anchor in which both of its ends 11 are outward turned and function in a fashion similar to that of the form previously described.

The intention is that the cluster 8 may be secured to the body so as to depend from the anchor at either end of the tube and 75 changed from time to time from one position to the other, as it may be desired to cause the bait to ride upon the surface of the water or become submerged as it is drawn by the line. The cluster 8 acts as a weight and 80 holds the body with the side thereof to which it is attached lowermost in the water. For instance: When the cluster is attached as shown in Fig. 1, the receding face 3 of the body is uppermost and the flat face 2 extends 85 in the lowermost position. When the cluster is attached to the body in the position shown in Fig. 2, the receding face is lowermost and the flat face extends in the uppermost position. When the bait is drawn 90 upon the water with the cluster positioned as shown in Fig. 1, the resistance of the water to the face 2 obstructs the forward movement of the body and because of the receding upper face 3 the front end of the 95 body becomes projected downwardly into the water and the body becomes submerged to a depth more or less extensive dependent upon its velocity. When the bait is drawn through the water submerged the resistance 100 of the water against the flat face 2 causes the body to waver and follow a zigzag course, and the receding face 3 tends to deflect the body downwardly. The entire weight of the bait is such that it will float at the surface of the water and therefore tends to rise to the surface when submerged because of its buoyancy, and the action of the water against the face 3, when the latter is in uppermost position, tends to deflect the bait 105 from the surface more or less according to its velocity. Thus, the operator, by manipu-

110

lating the line may cause the bait to travel through the water at a depth according to his judgment.

When the hook-cluster 8 is attached in the position shown in Fig. 2, the receding face 3 is lowermost and the bait when drawn through the water will tend to ride upon the surface. By thus shifting the hook-cluster from one position to the other the bait may be utilized readily for either surface or underwater operations. To change the position of the hook-cluster, the anchor is dislodged from the tube by pushing the eye 7 of the shank up through the tube so as to admit of the easy withdrawal of the anchor from the eye. The shank is then withdrawn from the tube and inserted therein from the opposite end, and after reinserting the anchor in the eye, the shank is again withdrawn from the tube and the anchor is thereby pulled into position.

The body may be decorated by a coating of paint or finishing material with a coloring as fancy may dictate and may have attached thereto additional hooks such as the tail-cluster 12.

What I claim is:—

1. In a device of the class described, a floating body having a vertical opening extending therethrough at right angles to its axis; a hook-cluster; an anchor for detachably securing the hook cluster at either end of the opening accordingly as the anchor is positioned; and means at the head end of the body for the attachment of the line.

2. In a device of the class described, a floating body having a receding face at its head end and having also a vertical opening extending therethrough at right angles to its axis, one end of the opening being adjacent the rear end of the face; a hook-cluster; a U-shaped anchor having an overturned end, and adapted to be drawn into the opening selectively at either end thereof and secure the cluster at the opposite end; and means for the attachment of a line at the head end of the body.

3. In a device of the class described, a floating body having a receding face at its head end and a vertical opening extending through the body at right angles to its axis; an anchor adapted to be projected

through the opening in the body; a hook-cluster adapted to be secured at either end of the opening by said anchor accordingly as the latter is positioned in the opening; and means for the attachment of a line at the head end of the body.

4. In a device of the class described, a floating body, the head end of which presents in part a flat face extending in a plane at right angles to the axis thereof and in part a receding face contiguous to the former face, said body having also a vertical opening extending therethrough; and detachable means positioned in the opening adapted for selectively securing a cluster at one end or the other of said opening.

5. In a device of the class described, a floating body having a diametral opening extending therethrough; means for the attachment of a line thereto at its head end; a hook-cluster having a shank with an eye in the end thereof adapted to be projected through the opening in the body; and an anchor consisting of a U-shaped wire having an overturned end, adapted to be introduced through the eye of the hook-cluster and to be drawn into said opening and secure said hook-cluster at the opposite end thereof, said overturned end being adapted to engage the body adjacent the corresponding orifice of the opening and prevent the anchor from being pulled therethrough.

6. In a device of the class described, a floating body having a receding face at one end and contiguous flat face at one end thereof and a diametral opening extending through the body; an open ended tube lodged in said opening and having protuberances therein positioned in opposite pairs; a removable anchor-wire adapted to be introduced from either end of the tube and positioned between the pairs of protuberances therein; a hook-cluster adapted to be connected with and held by the anchor; and means at the head end of the body for the attachment of a line.

In testimony whereof I affix my signature in presence of two witnesses.

JOHN W. DICKENS.
